SHOE WITH DETACHABLE HEEL

Elmer H. Brunmark, Worcester, Mass.

Application May 3, 1939, Serial No. 271,532

1 Claim. (Cl. 36—42)

This invention relates to shoes having detachable and replaceable heels. Substantial economy may be effected by the use of such heels, as the heel is the part of the shoe most subject to wear and the part which requires most frequent repair or replacement.

It is the general object of my invention to provide improved means for securing a heel to a shoe in such a way that it may be easily attached or released without the use of tools.

A further object is to provide a construction in which a portion of the attaching structure for a wood or similar heel may be formed directly in the heel itself, so that no additional or special parts need be applied to the heel. An important feature of my invention also relates to the application of a detachable heel to a shoe in such manner that a substantial saving in out-sole stock may be effected.

20 My invention further relates to arrangements and combinations of parts which will be herein-after described and more particularly pointed out in the appended claim.

25 A preferred form of my invention is shown in the drawing, in which

Fig. 1 is a side elevation of a portion of a woman's shoe, partly in section and embodying my invention;

Fig. 2 is a similar view of a part of the rear portion of the shoe, with the heel removed;

Fig. 3 is a side elevation of the detachable heel, partly in section;

Fig. 4 is a partial bottom view of the shoe, looking in the direction of the arrow 4 in Fig. 2;

30 Fig. 5 is a plan view of the heel, looking in the direction of the arrow 5 in Fig. 3;

Fig. 6 is a front view thereof, looking in the direction of the arrow 6 in Fig. 3;

Fig. 7 is an end view of an attaching plate, 40 looking in the direction of the arrow 7 in Fig. 2; and

Fig. 8 is a partial side elevation of the assembled shoe and heel, on a reduced scale.

I have shown my invention embodied in a woman's shoe having an out-sole 10, an insole 11, a slip-sole 12, an upper 14, and a heel 15 provided with an outer covering 16 and a tread portion 17.

The out-sole 10 preferably extends rearward only to the heel portion, where it provides a shoulder 20 (Figs. 1 and 4) against which the front edge 21 of the heel 15 abuts when the heel is attached to the shoe. The insole 11 extends the full length of the shoe as usual, and the upper 14 is in-turned and tacked or otherwise

secured to the under side of the insole, as indicated at 23 in Fig. 4.

An attaching plate 30, preferably of some light metal such as aluminum, is secured to the under side of the heel portion of the shoe in some suitable manner, as by rivets 31 extending upward through the insole 11 and headed above an insert or heel liner 32 underlying the slip-sole 12. The attaching plate 30 is provided with a longitudinally extending dove-tailed projection 35 having a longitudinal recess 36 and a stud 37 positioned in said recess.

The parts thus far described all constitute portions of the permanent structure of the shoe.

The detachable heel 15 is commonly formed 15 of wood or other similar material and the covering 16 thereof is commonly of leather or fabric and usually corresponds in color and material to the upper 14.

A dove-tailed recess 40 is formed in the upper surface of the heel 15 and is of such dimensions that the recessed portion of the heel is a close sliding fit over the projection 35 of the attaching plate 30. Preferably, the upper surface of the heel and the surfaces of the recess 40 are well 25 coated with shellac or other water-repellant material, so as to prevent changes in cross section of the recess 40 due to shrinking or swelling of the wood.

30 A locking spring 42 is secured in the bottom of the recess 40 in some convenient manner, as by nails or pins 43, and the spring 42 is provided with an opening 45 to receive the stud 37 when the parts are assembled. The outer end 46 of the spring 42 overlies the front upper edge of the 35 recess 40 and extends downward closely adjacent the front face 21 of the heel 15.

The spring end 46 is relatively inconspicuous when the heel is in place but affords convenient means for releasing the heel without requiring 40 the use of tools, by simple pressure of the finger thereon in the direction of the arrow *a* in Fig. 1.

The parts are assembled by presenting the heel at the rear of the shoe and sliding the same forward along the dove-tailed projection 35 until 45 the stud 31 enters the hole 45 in the spring 42 and locks the parts together, with the front surface 21 of the heel closely abutting the rear shoulder 20 of the out-sole 10.

The upper edge of the detachable heel closely 50 underlies the inturned upper 14, as shown in Fig. 8, so that merely a single separating line appears and no evidence of the detachable construction is readily apparent.

The matter of stopping off the out-sole 10 at 55

the front edge of the heel portion is of considerable importance, as it substantially reduces the amount of expensive out-sole stock required for each shoe. Obviously, two or more heels of different styles or heights may be provided for a single shoe, by use of which the utility of the shoes may be increased.

While I prefer the construction herein shown in which the dove-tailed recess 40 is formed directly in the material of the heel, thereby saving the expense of making and assembling the separate parts, I do not wish to be limited to this construction, otherwise than as set forth in the claim, but what I claim is:

A shoe having an attaching plate secured thereto below its heel portion and provided with a dove-tailed projection, a heel having a dove-tailed recess formed directly in the material of the heel and cooperating with said projection to secure said heel on said shoe, and locking means for said heel, said locking means comprising a spring on said heel coacting with a stud on said plate and having a release portion overlying the front edge of said recess and extending downward adjacent the front wall of said heel.

ELMER H. BRUNMARK.
